UNITED STATES PATENT OFFICE.

JOHN F. GLAVIN AND PATRICK K. MORRISSEY, OF RENSSELAER, NEW YORK.

CONCRETE-MOLD.

992,652.

Specification of Letters Patent. Patented May 16, 1911.

Application filed March 9, 1910. Serial No. 548,276.

To all whom it may concern:

Be it known that we, JOHN F. GLAVIN and PATRICK K. MORRISSEY, both of Rensselaer, in the county of Rensselaer and State 5 of New York, have invented certain new and useful Improvements in Concrete-Molds; and we do hereby declare the following to be a full, clear, and exact description of the invention, such as will enable others skilled in 10 the art to which it appertains to make and use the same.

The primary object of this invention is to provide improved simple and highly efficient means whereby the parts of a concrete 15 mold may be readily and easily assembled, and which will be secure as against displacement by the pressure of the concrete.

A further object is to so construct and arrange the parts as to leave no uninterrupted 20 spaces between the mold and the core to allow of the insertion of reinforcing bars, and to do away with all extra parts which would interfere with the removal of the retaining frames, which latter are adjustable both longitudinally and transversely and are free 25 from any direct attachment to either the mold or the core.

The invention will be hereinafter fully set forth and particularly pointed out in the 30 claims.

In the accompanying drawings, Figure 1 is a view in perspective of the vault mold. Fig. 2 is a fragmentary view showing the corner of the mold and the members of the 35 retaining frame. Fig. 3 is a fragmentary view of the members of the retaining frame of the core. Fig. 4 is a view in perspective of the cover mold. Figs. 5 and 6 are, respectively, longitudinal and transverse sec- 40 tional views of the cover mold.

Referring to the drawings, 1 designates an external mold, which is shown as composed of four telescoping L-shaped sections of sheet metal, with their ends overlapping so 45 as to permit of increasing or decreasing both the length and width of the mold. The mold sections are prevented from spreading by external frames 2. We have shown two of these frames, but more may be used if de- 50 sired. Each frame is composed of bars 3 extending longitudinally the full length of the mold, which bars at their ends are adjustably connected by cross bars 4, equal at least to the full width of the mold, the con- 55 nection being preferably made by nutted bolts passed through coincident openings,

several openings being formed in the bars at their meeting ends. We also employ angle irons at the points of connection of the side and end bars to add to the strength of the frame at the corners of the mold. Each frame, thus composed, rests upon stops 5 secured on the outside of the mold sections, and shown as consisting of angle plates. These frames are not attached to the mold 65 but merely rest on the seats. By adjusting the connections between the longitudinal side bars and the end bars the size of the mold may be readily enlarged or reduced. The upper retaining frame may be readily re- 70 moved without loosening any bolt, while to remove the lower frame it is only necessary to loosen the bolts of one of the cross bars.

The internal mold 7, which forms the core, is likewise composed of a series of L-shaped 75 telescoping sections of sheet metal adjustable both longitudinally and transversely. These sections on their inner sides have seats 8 to accommodate retaining frames 9, which are composed of longitudinal side bars approximately the full length of the core, and L-shaped end bars which are adjustably connected together and likewise connected to the side bars to allow the core to be enlarged 80 or reduced. We preferably employ two 85 inner frames, but more may be used if desired. The upper frame may be readily removed without loosening any bolt, but to effect the removal of the lower frame it is necessary to disconnect the side bars at one 90 end. There are no bars extending longitudinally or transversely across the mold or the core. In consequence not only may the frames be readily removed as stated, but reinforcing rods may be readily introduced 95 into the cement without hindrance.

The cover mold 10 is made up of four L-shaped telescoping sections of concavo-convex formation in cross-section, rounded at their corners, and capable of being adjusted 100 relatively to one another both longitudinally and transversely. They are supported by legs 12 arranged on opposite sides, which legs are fastened to the L-shaped sections. These legs are of right angular formation, 105 and each has a short horizontal portion at its upper end and an arc portion connecting the two right angular bars. The upper edge of the cover mold is surrounded by an adjustable frame which is composed of bars 110 13 paralleling the longitudinal sides of the mold which bars are of such length that

they will also at least equal the length of the mold, and they are adjustably connected by L-shaped end bars 14 which in turn are adjustably connected together, the 5 connections being preferably made by nutted bolts passed through coincident openings in the bars. The bars 13 rest upon and are bolted to the upper horizontal portions of the legs. The described construction 10 permits the size of the cover mold to be enlarged or reduced.

The core 15 of the cover mold is formed in substantially the same manner as the external mold, being composed of four L-shaped sections of concavo-convex formation and rounded at their corners, said sections being adjustable both longitudinally and transversely and they are connected by cross braces 16 each of which is composed 15 of two overlapping bars united by nutted bolts passed through coincident openings, the outer ends of said braces being curved to conform to the curvature of the L-shaped sections to which they are secured. The 20 frame for the core is composed of longitudinally extended bars 17, approximately the length of the core, and adjustably connected to L-shaped end bars 18 which in turn are adjustably secured to the bars 17 to permit 25 of enlarging or reducing the size of the core. When the two cover molds are in position they are held in place as against expanding by cross bars 20 bolted to the respective frames and preferably also to the legs 12 by 30 the same bolts that hold the bars 13.

In practice, the outer frames of the outer mold 1 and the inner frames of the inner mold 7 are adjusted by properly positioning the nutted bolts, and the L-shaped sections 40 composing the outer body mold are properly positioned within the lower external frame, and then the upper frame is dropped in place. After the sections of the inner mold have been built up around its upper 45 and lower frames this mold is placed within the outer mold and the apparatus is then ready for the concrete to be poured between the two molds. In making the concrete cover the outer mold is placed upon a smooth 50 slab and the concrete poured in to about two inches. The inner mold is then positioned and secured to the outer mold by cross bars 20. The concrete is then poured between the two molds. The operation takes 55 but a very short time, and dispenses with all troweling as ordinarily required. The cover will have round corners to materially add to its strength, and being concaved necessitates less building up of the sides 60 and ends of the vault.

The advantages of our invention will at once be apparent. It will be seen that the apparatus may be readily adjusted by changing only a few bolts. The longitudinal side bars of the retaining frames greatly 65 enhance the strength thereof and render bracing unnecessary.

We claim as our invention:

1. A cover mold composed of four L-shaped telescoping sections of concavo-convex formation, adjustable both longitudinally and transversely, legs secured to said mold and having upper bearing surfaces adjacent to the upper edge of the mold, a frame secured to said bearing surfaces of 70 the legs and composed of longitudinal side bars each at least the full length of the mold, telescoping end bars composed each of two right angular members adjustably connected together and to said side bars, a 75 core or inner mold composed of four L-shaped telescoping sections of concavo-convex formation, adjustable both longitudinally and transversely, a frame therefor composed of longitudinal side bars and 80 right angular end bars adjustably connected together and to said side bars, and braces extending transversely of the core and connected to the sides thereof, said braces being 85 composed of adjustably connected bars. 90

2. A cover mold composed of four L-shaped telescoping sections of concavo-convex formation, adjustable both longitudinally and transversely, right angular legs having arc shaped connecting portions secured to sides of the mold, a frame composed of longitudinal side bars attached to said legs, adjustably connected end members to which said side bars are adjustably connected, a core or inner mold composed of 95 four L-shaped telescoping sections of concavo-convex formation adjustable both longitudinally and transversely, a frame therefor composed of side bars and end bars adjustably connected together, the end bars 100 being composed of adjustably connected members, and transverse brace bars extending across both the inner and outer molds and adjustably connected to the longitudinal side bars on the frame of the outer 105 mold. 110

In testimony whereof, we have signed this specification in the presence of two subscribing witnesses.

JOHN F. GLAVIN:
PATRICK K. MORRISSEY.
